ATTORNEY.

UNITED STATES PATENT OFFICE.

LEWIS L. SCOTT, OF ST. LOUIS, MISSOURI.

PERCUSSION-DRILL.

1,308,811.

Specification of Letters Patent.

Patented July 8, 1919.

Application filed June 13, 1918. Serial No. 239,718.

To all whom it may concern:

Be it known that I, LEWIS L. SCOTT, a citizen of the United States of America, residing at the city of St. Louis, State of Missouri, United States of America, have invented a certain new and useful Percussion-Drill, of which the following is such a full, clear, and exact description as will enable any one skilled in the art to which it applies to make and use the same, reference being had to the accompanying drawings forming part of this specification:

My invention relates to a percussion drill and has for its object the production of a drill in which the drill bit is actuated by a free piston which in its forward stroke is unconnected with the other moving parts of the drill, whereby a quicker and more effective blow may be imparted to the drill bit than is possible where the piston actuating the bit is connected with the crank shaft.

Another object of my invention is to provide manually operated means whereby the free piston may be thrown out of operation.

In the accompanying drawing which illustrates one form of drill made in accordance with my invention, Figure 1 is a longitudinal section and Fig. 2 is an enlarged cross section taken on the line 2-2 of Fig. 1.

5 indicates the casing of the drill in which is arranged a piston 6 connected by means of a rod 7 with a crank shaft 8 journaled in the casing 5. The casing 5 together with the piston 6 forms an internal combustion engine of the two cycle type and the piston 6 is provided with the usual deflecting plate 9 for deflecting the charge which enters the combustion chamber 10 through a bypass adapted to be uncovered when the piston 6 reaches the near end of its stroke. The fuel is drawn into the crank case 12 through an opening 13 connected to any suitable fuel supply. The combustion chamber 10 is provided with the usual spark plug 14 for igniting the charge.

The charge in the combustion chamber 10 is adapted not only to actuate the piston 6 but also to actuate a free piston 15 which is arranged in the casing 5 in advance of the piston 6. Piston 15 is provided with an anvil 16 adapted to strike against the inner end of the drill bit 17 in order to actuate the same. In order that the charge may be compressed in the combustion chamber 10 between the forward end of the piston 6 and the rear end of the piston 15, I provide the casing 5 with

a detent 18 normally held in the path of the piston 15 by means of a coil spring 19 and the other end of the detent is provided with a cam face 20 adapted to be engaged by a cam 21 on a shaft 22. This shaft 22 is provided at its rear end with a beveled wheel 23 meshing with a beveled gear wheel 24 on the crank shaft 8. The cam 21 is held against rotation relative to the rod 22 by means of a key 25. This key 25, however, allows the cam 21 to be moved longitudinally of the shaft 22 by means of a milled head 26 so as to move the said cam 21 out of engagement with the cam face 20 on the detent 18. The discharge passage 27 leading from the combustion chamber 10 is of comparatively large cross section and is adapted to discharge into the forward end of the chamber 28 containing the free piston 15 after which the products of combustion are discharged into the air through a passage 29 of less area than the passage 27 so as to cause an excess of pressure in the forward end of the chamber 28 to assist in returning the piston 15 to normal position, as will hereafter be more fully described. 30 is a light coil spring arranged in front of the piston 15.

The operation of my drill is as follows: The charge is drawn in through the opening 13 when the piston 6 moves forward and is compressed in the chamber 12 when the said piston 6 moves toward the rear. Upon reaching the rear limit of its movement the bypass is uncovered to allow the charge to enter the combustion chamber 10 and strike against the deflecting plate 9 as is usual in the two cycle type of internal combustion engine. As the piston 6 moves forward, the piston 15 is held in position as shown in Fig. 1 of the drawings by the engagement of the detent 18 with its forward face. At or just after the time that the charge is exploded by the action of the spark plug 14, the detent 18 is withdrawn so as to allow the piston 15 to be forced freely forward by the explosion of the charge to cause its anvil 16 to strike against the end of the drill bit 17. The recoil caused by the striking of the drill bit 17 together with the action of the spring 30 throws the piston 15 back toward its initial position and this movement is assisted by the discharge of the contents of the combustion chamber 10 through the discharge passage 27 into the forward end of the chamber 28.

In case it is desired to operate the pis-

ton 6 without operating the free piston 15, as for instance, in withdrawing the drill, the milled head 26 is moved rearwardly along the shaft 22 so as to move the cam 21 out of engagement with the cam face 20 so that the detent 18 will not be withdrawn.

It will be understood that the forward end of the shaft 22 is used to rotate the drill bit 17 through any suitable mechanism 10 which is not shown, as it forms no part of the present invention.

Having fully described my invention, what I claim as new and desire to secure by Letters Patent of the United States is:

- 15 1. In a percussion drill, a cylinder, a piston in said cylinder, a drill bit, a second piston movable independently of said first named piston and actuated by the same charge, said second piston being adapted to 20 strike said drill bit, and means for locking said second piston during alternate strokes of said first piston.
- 25 2. In a percussion drill, a pair of pistons, a combustion chamber communicating motion to both said pistons, a crank shaft connected to one of said pistons, and retaining means for the other of said pistons controlled from said crank shaft.
- 30 3. In a percussion drill, the combination of a pair of pistons, of a combustion chamber for actuating both of said pistons, a crank shaft operatively connected to one of said pistons, a detent for the other of said pistons, and means operated from said crank shaft for controlling said detent.
- 35 4. In a percussion drill, the combination with a pair of pistons arranged one in front of the other, a combustion chamber arranged between said pistons and adapted to communicate power to both, of a crank shaft operatively connected to one of said pistons, a drill bit adapted to be struck by the other

of said pistons, a detent for said second named piston, and operative connections between said crank shaft and detent for controlling the latter. 45

5. In a percussion drill, the combination with a compression piston, of a free piston, both of said pistons being actuated from the same combustion chamber, locking means for retaining said free piston during the compression of the charge in the combustion chamber, and a drill bit actuated from said free piston. 50

6. In a percussion drill, the combination with a compression piston, of a free piston, both said pistons being actuated from the same combustion chamber, means for retaining said free piston in position during the compression of the charge, and a discharge 60 passage for discharging the contents of said combustion chamber forward of said free piston to assist in returning the same to normal position. 65

7. In a percussion drill, the combination with a compression piston, of a free piston, both said pistons being actuated from the same combustion chamber, locking means for positively retaining said free piston in position during the compression of the 70 charge, and a spring operating on said free piston to assist in returning the same to normal position. 75

8. In a percussion drill, the combination with a compression piston, of a free piston, both said pistons being actuated from the same combustion chamber, a crank shaft connected with said compression piston, a detent for said free piston controlled by said crank shaft, and manually operated means 80 for throwing said control out of operation. 85

In testimony whereof, I have hereunto set my hand and affixed my seal.

LEWIS L. SCOTT. [L.S.]
